UNITED STATES PATENT OFFICE

2,378,051

ADVERTISING DEVICE

William F. Vernon, Newton, Iowa

Application June 15, 1942, Serial No. 447,044

2 Claims. (Cl. 40—126)

This invention relates to an advertising device in the form of a display mirror wherein the product of the advertiser is shown in a unique manner in combination with a weather recording instrument.

The particular object of the invention is to provide an effective and economical construction for a mirror advertising device.

Other objects and benefits will be described in the following descriptions and drawings in which

Fig. 1 is a front elevational view of my complete advertising device;

Fig. 2 is a front elevational view of the glass front of the device of Fig. 1 showing the various transparent and mirror sections together with display and decorative sections as will later be explained;

Fig. 3 is a perspective view of the glass front section of my device with associated members as will be further explained hereinafter;

Fig. 4 is a perspective view of the parts which make up the rear section of my device as will later be explained in detail; and

Fig. 5 is an enlarged horizontal cross section of my complete device as it would appear on the section lines 5—5, Fig. 1.

Now referring to the drawings, and at the outset particularly to Fig. 4 the unitary back section of the device is composed of a heavy cardboard section 10 having openings 11 and 12 therein. Immediately back of the heavy section 10 is a lighter cardboard section 14 and both of these sections are combined together in a unit by means of the paper tape section 15 which is securely pasted on the back of section 14 and over the side and front edges of section 10. This entire back section is supported by the cord 22 through holes 22' as shown.

Now referring to Figs. 2 and 3 the front glass section 16 has transparent sections 26, 27, 28 and 29 provided by the decalcomania display means 30 and the mirror reflection means 31 applied to the back of the glass 16. Decorative means is also applied to the back of the glass 16 as is shown by the lines 19, 20 and 21. The glass 16 is first silvered, leaving apertures 26, 27, 28 and 29 as well as area 30 and strips 19, 20 and 21. Decalcomanias thereafter are applied on the strips. It will be appreciated that all of the foregoing construction may be standardized for all seed corn dealers as illustrated in this embodiment of the invention. However, the device may be adapted for individual dealers by attaching to the glass 16 in back of the transparent sections 26 and 29, paper cards 17 and 18 carrying the dealer's name and slogan. These cards, together with a sample of said corn 13 effectively advertise the individual dealer and his business while utilizing a standardized construction as illustrated and described. A thermometer 25 is inserted in

the opening 11 to attract the attention of the passerby.

The assembly of the front and back sections is effectively accomplished by the assembly of these sections whereupon corner clips 32 are applied over the assembled sections and effectively held together by brads 34 inserted through openings 33 in the corner section and driven into the heavy cardboard section 10. Thus, I provide an effective and economical mirror advertising device wherein the dealer's name and a sample of his wares is displayed, together with a thermometer or similar weather instrument.

Having thus described my invention, I now claim as new:

1. In an advertising device, a back section comprising a heavy cardboard element having openings therein for receiving advertising samples and a thermometer, a light cardboard element for closing the back of the heavy cardboard element, a light tape element for binding the heavy and light elements together, openings through the combined back section, and a support cord inserted through the openings; a glass front section having transparent areas to coincide with the openings in the heavy cardboard element and for displaying advertising media, display and decorative areas provided by applying opaque paint designs on the back of the glass section, mirror areas surrounding the transparent and opaque areas provided by applying reflector substance to the back of the glass section, and display cards attached to the back of the glass section over some of the transparent areas for displaying the dealer's name and slogan; and corner brackets for holding the front and back sections together whereby the device may be hung by the cord as a unitary advertisement.

2. In an advertising device, a back section comprising a heavy cardboard element having openings therein for receiving advertising samples and a thermometer, a light cardboard element for closing the back of the heavy cardboard element, and a light tape element for binding the heavy and light elements together; a glass front section having transparent areas to coincide with the openings in the heavy cardboard element and for displaying advertising media, display and decorative areas provided by applying opaque paint designs on the back of the glass section, mirror areas surrounding the transparent and opaque areas provided by applying reflector substance to the back of the glass section, and display cards attached to the back of the glass section over some of the transparent areas for displaying the dealer's name and slogan; corner brackets for holding the front and back sections together and means to support the combined sections from the back section as a unitary advertisement.

WILLIAM F. VERNON.
